UNITED STATES PATENT OFFICE.

JOSEPH OUIMETTE, OF SOUTHBRIDGE, MASSACHUSETTS.

SPRING-REPAIRER.

1,144,945.

Specification of Letters Patent. Patented June 29, 1915.

Application filed November 14, 1912. Serial No. 731,239.

To all whom it may concern:

Be it known that I, JOSEPH OUIMETTE, a citizen of the United States, residing at Southbridge, in the county of Worcester 5 and State of Massachusetts, have invented a new and useful Spring-Repairer, of which the following is a specification.

This invention relates to a device for repairing vehicle springs in use on automobiles, trucks, and the like, for preventing breakage and for absorbing the shocks.

The principal objects of the invention are to provide a device of this character which can be applied readily and firmly in such 15 a way that it is not in the least likely to get out of place, and which will be adjustable to provide for springs of different widths; also to provide a construction in which the parts can be reversed so that it can be used either 20 to bridge a clip when the break is at the clip or to apply to the end of the spring, and which can be used on a perfect spring to reduce the shock and the danger of breakage.

Reference is to be had to the accompanying drawings in which—

Figure 1 is a perspective view of a part of a broken spring with a preferred form 30 of this invention applied thereto; Fig. 2 is a side view of a spring showing the device applied at one side of the clip; Fig. 3 is a similar view showing another way of using it; Fig. 4 is a plan of one end of the bridge piece, and Fig. 5 is a perspective view of a removable element forming part of the invention.

The invention is illustrated in a form in which it comprises a main bridge piece 10 raised at the center to permit it to pass over the clip *a* by which the spring *b* is 40 ordinarily secured to the axle. In ordinary use the device is made to bridge this clip and to clamp the spring on opposite sides thereof. The bridge piece is provided with a transverse head 12 at each end having 45 elongated slots 13 therein near the edges. The lower faces of these ends are convex at 14 to fit the top surface of a spring of the usual elliptical shape. Passing through the perforations 13 are a pair of bolts 15 which 50 screw into bottom stay pieces 16. These stay pieces have their surfaces concave and slanted at 17 to fit the bottom of the elliptical spring, this surface being complementary to the surface 14. The bolts screw into these

pieces and check nuts 19 are provided below for fixing them in position.

For the purpose of more fully uniting and fixing the parts, especially when all the leaves of the spring are broken, a bottom piece 20 is provided having a width substantially the same as that of a leaf of the spring and a shape to fit the bottom of the spring. This piece is provided with heads 21 at the ends engaging over the edges of the stay pieces 16.

Three ways in which the device can be used are clearly shown in Figs. 1, 2 and 3, it being understood that when it is applied to a narrow spring all the parts are used except the stay pieces 16, and similar ones 70 are employed which have their screw threaded openings for the bolts nearer together. It will be obvious that when the parts are used in the position shown in Fig. 3, the device has to be reversed, and one of the stay 75 pieces is reversed relatively to the bridge piece. This constitutes an extremely rigid and firm device for the purpose intended, the fitting surfaces 14 and 17 preventing rocking of the parts on the spring and the 80 construction providing for securely holding all the elements in position even when all leaves of the spring are broken. I find in practice also that when the device is used as shown in Fig. 1 it furnishes means for 85 transmitting the shocks from one side of the spring directly to the other, thus equalizing the motion on both sides, and it makes the vehicle ride easier and prevents breakage.

While I have illustrated and described a 90 preferred embodiment of the invention I am aware of the fact that many modifications can be made therein by any person skilled in the art without departing from the scope of the invention as expressed in the claims. 95 Therefore I do not wish to be limited to all the details of construction herein shown and described, but

What I do claim is:—

1. As an article of manufacture, a spring 100 repairer comprising a bridge piece having integral transverse perforated ends for engaging one side of a spring, a pair of perforated stay pieces on the other side of the spring, and bolts connecting said stay pieces 105 to said bridge, the spring-engaging faces of the stay pieces being formed at an acute angle to the plane of the bridge and said

stay pieces being reversible, whereby the angular relation of the engaging faces of the bridge and stay pieces may be changed relatively to each other.

5 2. As an article of manufacture, a spring repairer comprising a bridge piece engaging one side of a spring, a pair of stay pieces engaging the other side of the spring, bolts connecting said bridge and said stay pieces, 10 and a rigid longitudinal member adapted to fit between the spring and the stay pieces,

the ends of said member engaging said stay pieces and being effective to prevent longitudinal separation thereof.

In testimony whereof I have hereunto set 15 my hand, in the presence of two subscribing witnesses.

JOSEPH OUIMETTE.
